UNITED STATES PATENT OFFICE.

REGINALD G. STANDERWICK, OF MARBLEHEAD, MASSACHUSETTS, ASSIGNOR TO GENERAL ELECTRIC COMPANY, A CORPORATION OF NEW YORK.

GOVERNING MECHANISM FOR PRIME MOVERS.

Application filed March 4, 1924. Serial No. 696,872.

To all whom it may concern:

Be it known that I, REGINALD G. STANDERWICK, a citizen of the United States, residing at Marblehead, in the county of Essex, State of Massachusetts, have invented certain new and useful Improvements in Governing Mechanism for Prime Movers, of which the following is a specification.

The present invention relates to governing mechanisms for prime movers wherein the prime mover drives a pump or other machine which delivers fluid under pressure and it is desired to govern the prime mover in accordance with the pressure delivered by such machine so as to maintain the pressure constant. In such installations the load on the prime mover may vary over a wide range and the object of my invention is to provide an improved governing mechanism which is simple in structure, reliable in operation and capable of regulating the prime mover over a wide range.

For a consideration of what I believe to be novel and my invention, attention is directed to the accompanying description and the claims appended thereto.

In the drawing, Fig. 1 is a side elevation partly in section of a prime mover provided with governing mechanism embodying my invention; Fig. 2 is an end view of the governing mechanism certain parts being shown in section; Fig. 3 is a detail sectional view of a cylinder and piston structure, and Fig. 4 is an outline of the set.

Referring to the drawing, 5 indicates a prime mover, here indicated as an elastic fluid turbine connected to drive a pump 6. The suction conduit for the pump is indicated at 7 and the discharge conduit 8. The pump is indicated diagrammatically and may be any suitable type of pump for pumping either liquids or gases. The admission of elastic fluid to the turbine is shown in the present instance as being controlled by a valve 9 which regulates the flow of the elastic fluid from a valve chest 10 to a passage 11 leading to the first stage nozzles of the turbine. Valve 9 has a stem 12 which extends out through the valve chest 10 and connects to a piston 13 which moves in a cylinder 14. The valve structure illustrated is shown only diagrammatically and by way of example and it will be understood that it is intended to represent any suitable valve structure. The upper end of cylinder 14,

that is its head, is provided with an extended portion 15 having an outer finished surface upon which slides a cap 16 which is connected to piston 13 by a rod 17. When piston 13 moves therefore cap 16 moves with it. Piston 13 and cylinder 14 form a usual type of fluid-actuated motor for actuating valve 9. The admission of actuating fluid to cylinder 14 is controlled by a pilot valve 18 which moves in a cylinder 19 and controls the passages 20 and 21 leading to cylinder 14 on opposite sides of piston 13. A well known type of pilot valve is indicated in the drawing, the space 2 between the valve members being connected to an inlet pipe 23 and spaces 24 and 25 beyond the valve members being connected to discharge pipes 26. The stem 27 of pilot valve 18 is pivotally connected to the central portion of a lever 28.

Projecting from the walls of pilot valve 19 are two arms 29 and 30 which at their ends support cylinders 31 and 32. In cylinder 31 is a piston 33 provided with a tubular extension 34 which slides in a guide 35 formed integral with the cover of cylinder 31. Piston 33 forms a movable abutment and is connected to one end of lever 28 by a rod 36. The upper end of rod 36 is pivoted to lever 28 as indicated at 37 and the lower end is connected to piston 33 by a tension spring 38 which holds it in engagement with the top wall of the piston, such lower end being pointed and engaging in a recess in the piston wall as shown particularly in Fig. 3. One end of spring 38 is fastened to a spring plug 39 and the other end is fastened to the outer portion of guide 35. Spring plug 39 is held between spaced nuts 40 which engage a threaded portion on rod 36. By turning nuts 40 the tension of spring 38 can be adjusted.

The underside of piston 33 is subjected to a pressure proportional to the pressure being delivered by pump 6. To this end I provide a pipe 41 which at one end is connected to pump discharge conduit 8. The other end leads to any suitable discharge point. In pipe 41 is provided means forming a small orifice 42 and beyond this as regards the direction of flow is a regulating valve 43, there being thus provided a space 44 between them. Connected to pipe 41 in the space 44 between orifice 42 and regulating valve 43 is a branch pipe 45 which connects to cylinder 31 beneath piston 33, 110

With this arrangement there is a drop in pressure across orifice 42 depending upon the adjustment of regulating valve 43. When valve 43 is moved toward the closed position the drop in pressure across orifice 42 becomes less while when it is moved toward the open position the drop in pressure becomes greater. When valve 43 is given a definite setting there will be a certain drop 5 in pressure across orifice 42 and hence a certain pressure in space 44 which pressure is proportional to and will vary directly with the pressure in conduit 8. By adjusting valve 43 I can always have the same operating pressure for the piston 33 irrespective of the pressure being delivered by the pump. This is an important consideration where it is desired that the governor shall operate over a wide range of pressures for 10 it enables me to set the governor spring 38 for operation with a certain pressure best suited for its characteristics, the governor being then adjusted for different pressures by changing the setting of valve 43. For 15 example, assume that the pump 6 is delivering fluid at a certain pressure and that valve 43 and spring 38 are set to maintain this pressure. If now it is desired to set the governor for some other pump pressure this 20 may be done by adjusting valve 43 so as to change the drop in pressure across orifice 42, leaving the setting of spring 38 the same.

In cylinder 32 is a piston 46 which is connected to the other end of lever 28 by a rod 35 47 and spring 48, the arrangement being similar to the connections already described between piston 33 and the lever 28. Cylinder 32 is connected by a pressure pipe 49 to the discharge side of a pump 50. Pump 50 40 pumps fluid, such as oil for example, from a tank 51, in which the pump is located and may be of any suitable type which delivers fluid at a pressure proportional to its speed. In the present instance, a pump of the gear 45 type is indicated in the drawing. It is driven by a shaft 52 connected to turbine shaft 53 by worm gearing 54. The pump is driven, therefore, at a speed proportional to the turbine, which means that it delivers 50 fluid at a pressure proportional to the turbine speed. Connected to pipe 49 is a discharge pipe 55 which leads back to tank 51 and is provided with a regulating valve 56 and a restricting orifice 57. Connected to 55 pipe 49 is a pressure relief valve 58 also. At 59 is indicated the intake strainer for pump 50.

It will be understood that while I have shown the governor having movable abutments in the form of pistons moving in cylinders, I may use other forms of abutments if desired.

Mounted on pilot valve stem 27 is an adjustable stop 60 in the form of two nuts 65 which engage a threaded portion on stem

27. Resting on stop 60 is a spring support 61 between which and a second spring support 62 is located a spring 63. Engaging the top of the spring support 62 is an arm 64 which is fastened to cap 16. Pilot valve 70 stem 27 passes freely through the openings in spring support 62 and arm 64 so that the arm and pilot valve stem may move relatively to each other and when they so move the compression of spring 63 is varied. 75

In operation, governor spring 38 is set so that when the desired average governor pressure exists in pipe 45, piston 33 is approximately in its mid-travel position; and valve 43 is set so that when the desired discharge pressure exists in pump conduit 8, the drop in pressure through orifice 42 will give the desired governor pressure. The oil governor comprising pump 50, piston 46 and spring 48 is used as a pre-emergency 80 governor, that is a governor which serves to take control of the turbine and prevent the speed going beyond a predetermined high value. The governor spring 48 is set for the desired governor operating pressure and valve 56 is set so that when the speed reaches a pre-determined high value, pump 50 will build up a pressure in pipe 49 which will move piston 46 to effect control of the turbine. Pressure relief valve 58 is set to limit 90 to a desired value the pressure which can be built up in pipe 49 and orifice 57 is made of such size that it limits to a safe value the speed for which the oil governor can be set by valve 56. During normal operation, piston 46 is at the bottom of cylinder 32 and the upper end of rod 47 serves as a stationary fulcrum for lever 28. 95

When during operation, the pressure in discharge conduit 8 increases beyond that 100 for which the governor is set, then the pressure under piston 33 will be increased and will move the piston upward thereby lifting pilot valve 18. This serves to admit motive fluid through passage 21 to the space above piston 13 and to permit motive fluid to escape from the space beneath piston 13. The piston will therefore be moved downward to close somewhat the valve 9 which will decrease the flow of elastic fluid to the turbine 110 115 so that the speed will decrease. With decrease in speed, the delivery pressure of pump 6 will decrease. Spring 63 which surrounds the pilot valve stem acts in parallel with governor spring 38 and when piston 13 moves downward arm 64 moves with it, pressing down on spring 63 and thereby increasing its pressure downward on the pilot valve. This results in restoring the pilot valve to its original position thereby preventing overtravel of the governor. 120

When the pressure in discharge conduit 8 decrease below the desired value, the pressure beneath piston 33 decreases whereupon spring 38 will effect a lowering of piston 130 125 130

and pilot valve 18 and a movement of piston 13 upward thus opening further valve 9 to increase the speed of the turbine and pump. When piston 13 moves upward it relieves somewhat the pressure on restoring spring 63. This decreases the spring pressure on piston 33 and it thereupon moves upward, lifting the pilot valve 18 so as to restore it to its original position.

10 As already stated, the oil governor is ordinarily inactive, the turbine being entirely under the control of the pressure governor. When the predetermined speed for which the oil governor is set is exceeded, however, it comes into play, piston 46 being then moved against the action of spring 48 to operate the pilot valve so as to effect the moving of valve 9 to a position where the desired speed is maintained. The oil governor operates valve 9 in the same manner as does the pressure governor and its operation will be obvious from the description already given.

From the foregoing description it will be seen that my governor mechanism is simple and compact in structure, and that by reason of the use of orifice 42 in conjunction with valve 43, said mechanism can be set to operate over a wide range of fluid pressures and in each case will have the same degree of regulation because the pressure actually operating on the governor piston may always be adjusted to the same normal value.

25 35 In accordance with the provisions of the patent statutes, I have described the principle of operation of my invention, together with the apparatus which I now consider to represent the best embodiment thereof, but I desire to have it understood that the apparatus shown is only illustrative and that the invention may be carried out by other means.

What I claim as new and desire to secure by Letters Patent of the United States, is:

45 1. The combination with a prime mover, a driven machine, and valve mechanism controlling the flow of actuating fluid to the prime mover, of means for regulating said valve mechanism comprising a fluid-actuated motor, a pilot valve, a lever connected to the pilot valve, a movable abutment connected to said lever, a conduit which conveys pressure from the driven machine, a conduit connecting the first named conduit to said movable abutment, and means defining passages of restricted area in the first-named conduit on opposite sides of the connection of the second named conduit therewith, one of such means being adjustable to vary the size of the passage.

50 55 2. The combination with a prime mover, a driven machine, and valve mechanism controlling the flow of actuating fluid to the prime mover, of means for regulating said

valve mechanism comprising a fluid-actuated motor, a pilot valve, a lever, an intermediate point of which is connected to the pilot valve, a movable abutment connected to each end of said lever, means supplying pressure to one of said abutments proportional to the speed of the prime mover, and means supplying pressure to the other abutment proportional to an operating condition of the driven machine.

3. The combination with a prime mover, a driven machine, and valve mechanism controlling the flow of actuating fluid to the prime mover, of means for regulating said valve mechanism comprising a fluid-actuated motor, a pilot valve, a lever, an intermediate point of which is connected to the pilot valve, a casing for the pilot valve, two movable abutments carried by the pilot valve casing and connected to the ends of said lever, means supplying pressure to one of said abutments proportional to the speed of the prime mover, and means supplying pressure to the other of said abutments proportional to an operating condition of the driven machine.

4. In a governing mechanism for prime movers, the combination of a movable abutment, a conduit for conveying pressure, means in said conduit forming spaced passages of restricted areas, the area of one of which is adjustable, and a conduit connecting the space between said passages to the movable abutment.

5. The combination with a prime mover, a driven machine and valve mechanism controlling the admission of elastic fluid to the prime mover, of means for regulating the valve mechanism comprising a governor having a movable abutment, a conduit for conveying fluid pressure which bears a definite relation to an operating condition of the prime mover, means forming a passage of restricted area in said conduit, a second means spaced from the first means and forming another passage of restricted area, said second means being adjustable to vary the area of the passage, and a conduit for conveying pressure from the space between said two passages to the movable abutment.

6. The combination with a prime mover having a valve mechanism controlling the admission of motive fluid thereto, of a pair of pumps connected with and driven by the prime mover, separate pressure responsive devices connected with each of said pumps, said devices being operatively connected with the valve mechanism to move the latter in response to certain pressure values delivered by said pumps, and separate pressure adjusting means interposed between said pumps and pressure responsive devices to regulate said pressure values.

7. The combination with a prime mover having a valve mechanism controlling the

admission of motive fluid thereto, of a pair of fluid pressure pumps driven by the prime mover, a lever by which the valve mechanism is operated to control the prime mover, separate pressure responsive devices connected with each of said pumps to receive fluid pressure therefrom, said devices comprising spring loaded movable abutments operatively connected with the lever to move the same in response to certain pressure values delivered by said pumps, and separate pressure regulating means, including an orifice and a valve, provided in the connection between each pump and its respective pressure responsive device.

8. The combination with a prime mover and a fluid pressure creating machine driven thereby, of a governing mechanism for the prime mover, comprising a valve controlling the admission of motive fluid to said prime mover, a fluid actuated motor connected therewith to operate the valve, a pilot valve for the motor, a lever having an intermediate point pivotally connected with the pilot valve, means including a spring forming a connection between the movable member of the motor and the pilot valve, a movable

abutment pivotally connected with each end of the lever, casings for said abutments to which fluid pressures are supplied to move said abutments and operate the pilot valve, means connected with the abutments for adjustably loading said abutments in opposition to the pressures acting thereon, a conduit connected with the fluid pressure creating machine to receive fluid pressure therefrom, an orifice forming a passage of restricted area in said conduit, a valve in said conduit spaced from the orifice in the direction of fluid flow and forming a second passage of adjustably restricted area, a conduit connecting the casing at one abutment with the first-named conduit at a point between said passages of restricted area, a pump driven by the prime mover, a conduit to which said pump supplies fluid under pressure connected with the casing of the other abutment, and means connected with said conduit for regulating the pressure therein.

In witness whereof, I have hereunto set my hand this 29th day of February, 1924.

REGINALD G. STANDERWICK.

- admission of motive fluid thereto, of a pair of fluid pressure pumps driven by the prime mover, a lever by which the valve mechanism is operated to control the prime mover, separate pressure responsive devices connected with each of said pumps to receive fluid pressure therefrom, said devices comprising spring loaded movable abutments operatively connected with the lever to move the same in response to certain pressure values delivered by said pumps, and separate pressure regulating means, including an orifice and a valve, provided in the connection between each pump and its respective pressure responsive device.

8. The combination with a prime mover and a fluid pressure creating machine driven thereby, of a governing mechanism for the prime mover, comprising a valve controlling the admission of motive fluid to said prime mover, a fluid actuated motor connected therewith to operate the valve, a pilot valve for the motor, a lever having an intermediate point pivotally connected with the pilot valve, means including a spring forming a connection between the movable member of the motor and the pilot valve, a movable abutment pivotally connected with each end of the lever, casings for said abutments to which fluid pressures are supplied to move said abutments and operate the pilot valve, means connected with the abutments for adjustably loading said abutments in opposition to the pressures acting thereon, a conduit connected with the fluid pressure creating machine to receive fluid pressure therefrom, an orifice forming a passage of restricted area in said conduit, a valve in said conduit spaced from the orifice in the direction of fluid flow and forming a second passage of adjustably restricted area, a conduit connecting the casing at one abutment with the first-named conduit at a point between said passages of restricted area, a pump driven by the prime mover, a conduit to which said pump supplies fluid under pressure connected with the casing of the other abutment, and means connected with said conduit for regulating the pressure therein.

In witness whereof, I have hereunto set my hand this 29th day of February, 1924.

REGINALD G. STANDERWICK.

In witness whereof, I have hereunto set
my hand this 29th day of February, 1924.
